United States Patent Office.

OTIS B. BARTLETT AND GEORGE E. BARTLETT, OF LEWISTON, MAINE.

Letters Patent No. 102,751, dated May 10, 1870.

IMPROVED STOVE-PIPE ATTACHMENT.

The Schedule referred to in these Letters Patent and making part of the same.

To all whom it may concern:

Be it known that we, OTIS B. BARTLETT and GEORGE E. BARTLETT, of Lewiston, in the county of Androscoggin and State of Maine, have invented a new and useful Improvement in Bands for Stove-Pipes; and we do hereby declare that the following is a full and exact description of the same, reference being had to the accompanying drawings and to the letters of reference marked thereon.

This invention relates to that class of stove-pipe attachments which use a band bolted to the pipe, and consists in the employment of a standard and double hook, by means of which the entire device is adapted for application to horizontal stove-pipes.

In the drawings—

Figure 1 represents a side elevation of our improved attachment as applied to a pipe, and

Figures 2, 3, 4, and 5 views of parts detached.

A represents a pipe elbow upon which is bolted the band B. This band is preferably made with grooves formed in the band itself, as clearly shown in fig. 2.

Upon this band is slipped the standard C, which is constructed in two parts, as shown in figs. 4 and 5.

These parts are each provided with semicircular

grooves c c, which, when the parts are united by means of a screw, form orifices for the reception of the bent rod d, as shown in fig. 1.

e represents a double hook, which is held in any one of the grooves b.

The device as a whole is simple and inexpensive. We do not claim as our invention the band provided with grooves, as shown, for this we know to be old; but

Having thus fully described our invention,

What we claim as new, and desire to secure by Letters Patent, is—

1. The vertical standard C, in combination with the band B, as described, for the purpose set forth.

2. The band B, standard C, and double hook e, when combined as described, for the purpose set forth.

This specification signed and witnessed this day of , 186

OTIS B. BARTLETT,
GEORGE E. BARTLETT.
